PACKING FOR MOBILE DAM
STRUCTURES

Theodor Becher, Wiesbaden, Germany, assignor
to Maschinenfabrik Augsburg-Nürnberg, A. G.,
Nuremberg, Germany, a corporation of Germany

Application July 18, 1935, Serial No. 32,095
In Germany September 20, 1934

4 Claims. (Cl. 61—22)

This invention relates to dams, and more particularly to sealing or packing devices for movable dam structures, such as gates, roller dams and the like.

5 Movable dam structures of the roller type usually comprise a body adapted to be positioned across a stream or water course for the purpose of damming up the water. It has been the practice to mount the two ends of dams of this type in 10 masonry or concrete piers, and to utilize suitable hoisting mechanism for moving the damming structures into and out of damming position.

The main body portion of a dam of the roller type may have one or more aprons or flaps 15 cured thereto and extending therefrom. The apron, which is usually arcuate in cross section, depends from the main body or drum of the dam structure and its lower longitudinal edge is adapted to rest on a sill or armature in the bed of the 20 stream or water course.

Means of some kind have to be employed whereby the joint between the lower portion of the 25 movable dam structure and the sill is made tight when the dam structure is in its damming position, so that water will not flow thereunder.

In some instances the sills have been provided with a sealing strip or packing for engaging the lower longitudinal edge portion of the dam structure. In other instances suitable sealing or 30 packing means have been formed along the lower longitudinal edge of the dam structure for engaging the sill. Sealing and packing means of the latter type have been constructed in various ways. One form of such means which has gone 35 into extensive use has comprised a water chamber formed along the lower longitudinal edge of the dam structure. Such water chamber may be substantially rectangular in cross section and it may have a movable and flexible front wall disposed on the upstream side of the dam structure. Furthermore, the front wall of the water chamber is so formed that said chamber is in 40 communication with the water in the pool on the upstream side of the dam structure.

45 The front wall of the water chamber usually carries a sealing or packing strip for engaging the sill in the bed of the stream or water course, and suitable means are provided for maintaining the front wall of the water chamber in contact 50 with the sill, when the damming structure is in damming position.

Since the movable dam structure is subject to considerable flexing or distortion as the result of the pressure of the water in the pool on the upstream side thereof, and since this deflection or

distortion of the dam structure varies throughout the length thereof, being greater at the center of the dam structure than near its ends, obviously means should be provided for maintaining the sealing or packing strip uniformly and tightly in engagement with the sill, throughout the entire length thereof, and the present invention relates to an improved construction of the sealing or packing means.

An object of the invention is to provide an improved bottom sealing or packing means for movable dam structures and the like, wherein the sealed joint between the dam structure and its supporting sill will remain tight in the event the dam structure bulges or becomes distorted under 15 the influence of the pressure of water thereagainst.

Another object of the invention is to provide improved means for resiliently maintaining the sealing or packing means of a movable dam structure against the floor of a water channel controlled by the dam structure when the dam structure is in damming position.

Another object of the invention is to provide an improved sealing or bottom packing means for 20 movable dam structures and the like, in which the sealing or packing means carried by the dam structure, comprises a sealing strip mounted on a plate disposed at the front of a water chamber on the upstream side of the dam structure and 25 resiliently connected to a wall of the chamber for movement toward and away from the floor of the water channel.

Another object of the invention is to provide an improved sealing or packing means of the 30 above mentioned type, in which the means for resiliently maintaining the packing strip in engagement with the floor of the water channel includes 35 a plurality of spring elements which are mounted in a water tight compartment on the downstream side of the dam structure.

Another object of the invention is to provide an improved sealing or packing means of the 40 above mentioned type which is useful where the level of the water in the lower pool is lower than the sealing strip.

Another object of the invention is to provide an improved sealing or bottom packing means for movable dam structures and the like, which is 45 simple in construction, and reliable and exact in function under all conditions of service.

The invention also comprises certain new and useful improvements in the construction, arrangement and combination of the several parts 50

of which it is composed, as will be hereinafter more fully described and claimed.

In the accompanying drawings:—

Figure 1 is a transverse section through a movable dam structure of the roller type, having an improved bottom sealing or packing means constructed according to the present invention;

Fig. 2 is an enlarged cross section of the lower portion of the dam structure shown in Fig. 1, showing the bottom sealing or packing means in detail;

Fig. 3 is a plan of a portion of the bottom sealing or packing means; and

Fig. 4 is a diagrammatic view, partly in section, illustrating the manner in which the movable dam structure is sealed against the sill on the bed of a stream.

Referring to the drawings and especially to Fig. 1, a portion of the usual floor formed in the bed of a stream or water channel to be controlled by a movable dam structure, such as a drum weir or roller dam, is indicated at 11.

As is customary, the floor 11 is formed with a sill 12 against which the bottom of the weir or movable dam structure is adapted to contact.

In the present instance the floor 11 is shown as being constructed of concrete or other cementitious material. However, it is to be understood that the floor 11 may be constructed from any other suitable masonry material. In order to prevent undue wear, the surface of the sill 12 is usually formed from suitable metal, as shown in Figs. 1 and 2.

The movable dam structure or gate illustrated in the present instance is of the roller type, comprising a hollow sheet metal cylinder or drum 13, which is adapted to be raised and lowered in any suitable or known manner.

Depending from the drum 13 is an apron 14, 40 arcuate in form, and having its upper edge suitably secured to the drum body. The lower edge of the apron 14 is disposed a suitable distance from the body of the drum and any suitable means may be employed for rigidly bracing the apron to the drum, such as struts 15, 16, 17 and 18, or the like, (see Fig. 1).

The lower or free edge of the apron 14 is formed with a suitable water chamber 19 which extends longitudinally of the apron for the entire length thereof, as shown in Fig. 4. This water chamber may be substantially rectangular in cross section, as shown best in Fig. 2, and said water chamber has rigid walls 20, 21 and 22, and a movable front wall 23.

The walls of the water chamber 19 are preferably formed of sheet metal, wall 20 being suitably secured to the strut 17, wall 22 being suitably secured to the struts 18, and wall 21 being secured to cross members 24 connecting struts 17 and 18, as shown in Figs. 1 and 2.

When the movable dam structure is in the position shown in Figs. 1 and 2, the wall 20 of the water chamber 19 is disposed uppermost and accordingly in order to clarify the description this wall will be referred to as the upper side wall of the water chamber. Likewise, wall 21 will be referred to as the rear wall of the water chamber, and wall 22 will be referred to as the lower side wall of said water chamber.

The front wall 23 of the water chamber 19 is preferably formed from a flexible plate having one of its longitudinal edges pivotally connected to the lower edge of wall 22, by hinges 25, as shown in Figs. 1, 2 and 3.

The front wall or plate 23 bridges the space

between the outer edges of the side walls 20 and 22. However, the edge of plate 23 adjacent side wall 20 is bent or turned inwardly, as indicated at 26, Fig. 2, so as to provide a gap or slot 27 between it and said side wall.

5

When the movable dam structure is in submerged position, as shown in Fig. 1, the front wall 23 is disposed along the bottom of the water chamber 19 and the inturned edge 26 is disposed adjacent to the top of said water chamber, so that water may enter into the chamber 19 through the slot 27.

Mounted on the underside of the plate 23, is a plate 28 carrying a sealing or packing strip 29. The sealing or packing strip 29 is preferably formed from rubber or rubber composition which is secured to plate 28 by vulcanizing, as indicated at 30, Fig. 2. By utilizing a strip of rubber for the sealing means, when the movable dam structure is lowered into engagement with the sill 12, a tight seal for preventing leakage of water through the joint between the movable dam structure and the floor of the water channel will be had.

As shown in Fig. 2, the sealing strip 29 is substantially triangular in cross section, so as to provide a comparatively thick portion of rubber throughout the central portion of the sealing strip. In this way the sealing strip will have sufficient resiliency so that the same will completely fill uneven surfaces in the sill 12.

Due to the pressure of the water held in the stream by the movable dam structure and bearing against the upstream side of said dam structure, it is obvious that the movable dam structure is subject to bending or flexing, from end to end.

Damming structures of the type herein shown and described have been constructed with lengths 100 feet and more, and when such damming structures are installed in a stream, they are supported only by piers at each end thereof. The damming structures may have a damming height of 20 or more feet, and therefore, the pressure of the water against the upstream side of the drum 35 13 and apron 14 flexes the same, so that the middle portion thereof is disposed downstream a slight distance from the ends thereof.

With the drum 13 and apron 14 thus flexed or bowed, obviously the parts constituting the water chamber 19 will also be bowed or flexed, as shown in Fig. 4, and with the central portion of the water chamber 19 thus flexed downstream, it will be appreciated that the sealing means for the bottom of the dam structure will not engage the central portion of the sill 12, as firmly as at the end portions of said sill.

Therefore, in order to maintain the sealing strip 29 uniformly in engagement with the sill 12 throughout the length thereof, individually adjustable spring means are provided, said spring means being constructed in the manner next described.

Connected at one end to the movable front wall 23 and extending upwardly through the water chamber 19 and passing through the wall 21 of said water chamber, is a plurality of rods 37. As shown in Fig. 4, the rods 37 are spaced apart at suitable intervals throughout the length of the movable dam structures.

70

The rods 37, which are pivotally connected to the front plate 23 by pivot pins 36, as shown in Fig. 2, also extend through a box like member 42 disposed on the upper side of the water chamber 19. Wall 21 of the water chamber 19 constitutes

75

the bottom of box 42. The box also has side walls 43 and 44, and a top 45.

Where the rods 37 pass through the wall 21 there are packing glands 41 which prevent the 5 escape of water from the chamber 19 into the box 42.

The upper end portion of each rod 37 is threaded, as at 38, for the reception of nuts 39 and 40, the latter nuts serving as lock nuts for the 10 nuts 39.

Disposed within the box 42 and encircling each rod 37, is a volute expansible spring 46. One end of the spring 46 bears against the top 45 of the box 42 and the other end of said spring bears 15 against a collar 47 mounted on the rod 37. If so desired a nut mounted on the threaded portion of the rod 37 may constitute the collar 47.

The tension of the springs 46 is adjusted by means of the collars 47, and when the movable 20 dam structure is moved away from the sill 12, outward movement of the front wall 23 will be limited by nuts 39 engaging the wall 45.

In the drawings nut 39 is shown spaced from the wall 45. This is due to the fact that the 25 movable front wall 23 has been swung inwardly in the water chamber 19 on hinges 25, due to the engagement of the sealing or packing strip 29 with the sill 12 when the movable dam structure is in its submerged or lower position.

With the parts in the position shown in Figs. 1 30 and 2, obviously the springs 46 will be compressed more than will be the case when the device is out of engagement with the sill 12 and the front wall 23 is in the extended position above described. However, the initial compression given 35 to the springs 46 by relative adjustment of the nuts or collars 47 will be such as to enable the sealing strip 29 to be urged tightly against the sill 12, irrespective of variations in the relative distance between the lower portion of the movable dam structure and said sill, due to bending or flexing of the dam structure resulting from the pressure of the water in the pool on the upstream side thereof.

Augmenting the action of the springs 46 is the 45 pressure of the water in chamber 19 against the front wall 23, since the water in chamber 19 transmits the pressure of the head water which enters the chamber 19 through slot 27 to the plate 23, whereby the sealing or packing strip 29 is 50 pressed against the sill 12.

Preferably the plates used in forming the front wall 23 should be constructed from suitable resilient sheet material, and the characteristics of 55 the material used in forming plates 23 and 28 should be such that the plates will withstand the tensional and crushing strain to which they are subjected. By employing suitable inexpensive but strong sheet metal in constructing the plates 23 and 28, and by vulcanizing the rubber strip 29 on to plate 28 by any suitable method, it has 60 been found that a satisfactory sealing and packing means will be provided for the device, which packing means will have a life substantially equal to the expected life of the dam structure without requiring replacement thereof.

By employing the series of springs 46 and by spacing said springs at suitable intervals apart, unduly strong bending of the front wall 23 will be 65 obviated, since said springs will function to brace the wall 23 throughout the length thereof and thereby prevent undue distortion of the same.

By adjustably tensioning the springs 46 by 70 means of the rods 37 and associated parts, various tensions can be imparted to the several

springs throughout the length of the dam, so as to impart sufficient pressure against the front wall 23 to firmly seat the sealing strip 29 against the sill 12.

Obviously, the portion of the sill 12 which is 5 engaged by the sealing strip 29 may have an uneven surface, and by employing flexible plates 23 and 28 and the rubber sealing strip 29, and by urging the sealing member towards said sill by the plurality of adjustable springs 46, the 10 sealing member can be made to conform to the surface of the sill 12.

The specific type of sealing means for a movable dam structure herein shown and described is especially useful where the level of the water 15 in the lower pool is lower than the sealing strip. In Fig. 1 the level of the water in the pools on both sides of the movable dam structure is indicated, and it will be noted that the normal height of the water in the downstream pool is shown 20 as being slightly lower than the point of the sill 12 engaged by the sealing strip 29. By constructing the device in the manner herein shown and described, the springs 46 will be located above the water in the lower pool, so as to be readily 25 accessible for inspection, lubrication, adjustment and replacement.

Furthermore, by this improved construction the springs 46 function only to take care of the forces which occur when the sealing strip 29 slides 30 on to the sill 12. The whole device, therefore, will last much longer and it will only be necessary to lubricate the springs from time to time. This can be accomplished without difficulty due to the accessibility of the springs 46, which has 35 been heretofore pointed out. As will be understood, since the springs are readily accessible, possible damage or defects thereof can be easily detected without difficulty. It will, therefore, be understood that by constructing the sealing 40 means in the manner herein described, the whole device will last much longer than is the case with similar devices of prior construction.

While the present invention is particularly useful in conjunction with water gates of the roller 45 type, it is in its broader aspects, however, not limited in its application to gates of any particular specific design.

From the foregoing description considered in connection with the accompanying drawings, it 50 is believed that the construction, operation and advantages of the invention will be clearly understood. It is desired to point out, however, that while a certain specific embodiment of the invention has been illustrated and described the 55 invention is readily capable of various other mechanical embodiments within the spirit and scope of the invention as defined in the appended claims.

Having thus described my invention, what I 60 claim is:—

1. A device of the class described comprising a movable dam structure having a water chamber formed thereon, a front wall hingedly connected along one edge to said water chamber, a resilient 65 packing strip on said front wall for engaging the sill of a dam to seal the joint between the sill and said movable dam structure, a water tight box mounted on said movable dam structure on the rear side of said water chamber, rods 70 pivotally connected to said front wall and extending through said water chamber and said box, and a tension element disposed in said box and encircling each rod for urging said front wall forwardly towards the sill of the dam. 75

2. A device of the class described comprising a movable dam structure having a water chamber formed thereon, a front wall hingedly connected along one edge to said water chamber, 5 a resilient packing strip on said front wall for engaging the sill of a dam to seal the joint between the sill and said movable dam structure, a water tight box mounted on said movable dam structure on the rear side of said water chamber, rods pivotally connected to said front wall and extending through said water chamber and said box, a tension element disposed in said box and encircling said rod, said tension element bearing at one end against the rear upper wall of said box and at the other end against a collar on the rod, for urging said front wall forwardly towards the sill of the dam, and a nut mounted 10 on the threaded portion of said rod for limiting the outward swinging movement of said front wall.
- 10 15 15 20 25 30 30
3. A device of the class described comprising a movable dam structure having a water chamber formed thereon, a front wall hingedly connected along one edge to said water chamber, a resilient packing strip on said front wall for engaging the sill of a dam to seal the joint between the sill and said movable dam structure, a box-like member mounted on said movable dam structure on the rear side of said water chamber, rods pivotally connected to said front wall and extending through said water chamber and said box, means carried by said rods for limiting the swinging 20 movement of said front wall, and tension elements disposed in said box for urging said front wall forwardly towards the sill of the dam.
